UNITED STATES PATENT OFFICE.

MICHAEL J. HARRINGTON AND JOHN J. HARRINGTON, OF LAURIUM,
MICHIGAN.

BOTTLE-STOPPER.

No. 821,638.

Specification of Letters Patent.

Patented May 29, 1906.

Application filed October 31, 1905. Serial No. 285,263.

To all whom it may concern:

Be it known that we, MICHAEL J. HARRINGTON and JOHN J. HARRINGTON, citizens of the United States, residing at Laurium, in the county of Houghton and State of Michigan, have invented new and useful Improvements in Bottle-Stoppers, of which the following is a specification.

Our invention is a stopper designed to render a bottle non-refillable; and it consists in a valved stopper embodying certain novel features of construction hereinafter described and claimed.

The stopper-valves are so constructed that it is impossible for any fluid to be injected or forced into the bottle. Also the stopper is provided with catches which make it impossible without complete destruction of the stopper or bottle to remove it from the bottle after it is put in.

A further novel feature is a screw for locking the valve closed, so that no liquid can escape from the bottle while in transit or prior to its first opening, and a seal can readily be applied to said screw which will guarantee proper origin and character of the contents of the bottle. The stopper is constructed in halves for the purpose of allowing the valves to be readily put in place, the halves being put together before the stopper is put in the bottle.

The invention is illustrated in the accompanying drawings, in which—

Figure 1 is a vertical sectional view of the stopper in place. Fig. 2 is an elevation of the stopper removed from the bottle. Fig. 3 is an elevation of the stopper, taken at right angles to the preceding view. Figs. 4 and 5 are front and side elevations, respectively, of the catches for preventing withdrawal of the stopper.

Referring specifically to the drawings, 15 denotes the neck of a bottle, an internal shoulder 16 being produced where the neck joins the body of the bottle, which shoulder co-operates with a pair of catches, to be hereinafter described, to prevent withdrawal of the stopper. The stopper comprises a cylinder 5, which is open at the bottom and fits with- 45 in the bottle-neck and is formed at its top end with a cap 17, having an outwardly-extending flange 18, which rests on the top edge of the bottle-neck. Between the cylinder and the wall of the bottle-neck is a packing

of cork or other suitable material 4 to prevent leakage of the contents of the bottle. Inside the cylinder are valve-seats 6 and 7, respectively, which are arranged one above the other. The lower seat 7 receives a ball-valve 2 and the upper seat 6 a hemispherical valve 3. The latter valve has at its bottom a depending stem 20 for guiding its movement and preventing displacement. At the top of said valve 3 are several projections 21 for spacing it from the outlet-opening of the cylinder and preventing its closure by the valve when the bottle is inverted to pour out its contents. The diameter of the stem 20 is less than that of the valve-seat opening, so as to not obstruct the free flow of the contents of the bottle therethrough. The outlet from the cylinder is through a threaded opening 22 in the cap 17, which opening may be closed by a screw-plug 1. The plug is of such length that when inserted its lower end bears on the valve 3 and holds it firmly seated and prevents escape of the contents of the bottle when in transit. To pour out the contents of the bottle, the plug is removed and the bottle inverted in the ordinary manner. As 75 stated, a seal may be applied over this plug when the package is put up. The lower end of the cylinder 5 extends below the bottle-neck and into the body of the bottle and carries on opposite sides rigid catches 9, engaging under the shoulders 16 to prevent withdrawal of the stopper. The catches have pivots 11 seated in bearing-recesses 12 in the wall of the cylinder, and behind each catch a flat spring 10 is secured for throwing them 90 outwardly into operative position. The lower ends of the catches are beveled, as at 28, below the pivots, which ends strike the wall of the cylinder and prevent excessive outward movement of the catches. The 95 wall of cylinder is cut-away or recessed, as at 29, so that when it is to be inserted into the bottle-neck, the catches will swing back into said recesses to enable them to pass through the bottle-neck. When the catches pass the 100 neck, they are swung out into position under the shoulder 16, as shown in Fig. 1, by the springs 10. That portion of the cylinder extending below the bottle-neck is formed with a large opening 8 to permit the contents of the bottle to flow readily into the valve-chamber. As stated, the cylinder will be made in two sections or halved to permit

the proper and easy placing of the valves. One of the sections has a tenon 14 fitting in a notch in the other section to prevent separation of the parts.

5 A stopper constructed as herein described is reliable and efficient in operation and effectively serves the purpose for which it is intended. No specially-constructed bottle is required, and it can be readily applied to 10 any ordinary bottle having an internal shoulder, as herein described. All the contents of the bottle can be poured out, and the valve will work at any angle, allowing the contents to flow freely through the stopper. To remove the stopper from the bottle, it will be 15 necessary to drill it out, and thus destroy it, or to smash the bottle, thus assuring the non-use of the bottle after it is emptied.

Having thus described our invention, what 20 is claimed as new, and desired to be secured by Letters Patent, is—

1. A bottle-stopper having at its top end a discharge-opening, and a valve under the same and a removable plug for closing the 25 discharge-opening, and bearing on the valve to hold it seated.

2. A bottle-stopper comprising a cylinder having a cap provided with a threaded out-

let-opening and a valve within the cylinder, and a screw-plug fitting in said opening and 30 adapted when inserted to bear upon the valve and hold it closed.

3. A bottle-stopper comprising a cylinder of sufficient length to project at its lower end below the neck of the bottle into the body 35 thereof, and having a rigid catch which is pivoted at its lower end in the wall of the said lower end of the cylinder and has a spring which acts to force out its upper end under the shoulder of the bottle.

4. The combination with a bottle having an internal shoulder, of a stopper comprising a valved cylinder which extends at its inner end below said shoulder and has recesses in the sides of said end, and rigid catches which 45 are pivoted in said recesses and have springs adapted to force their upper ends out behind the shoulder.

In testimony whereof we have signed our names to this specification in the presence of 50 two subscribing witnesses.

MICHAEL J. HARRINGTON.
